(57) **CLAIM**

The ornamental design for a pneumatic tire, as shown and described.

DESCRIPTION

FIG. 1 is a perspective view of the pneumatic tire showing my new design, it being understood that the tread pattern repeats circumferentially throughout the outer circumference and shoulder of a tire, the opposite side perspective view being identical thereto;

FIG. 2 is a side elevational view of the pneumatic tire shown in FIG. 1; and,

FIG. 3 is an end view of the pneumatic tire shown in FIG. 1.
